DISPOSABLE SANITARY PAD

Robert Celander, Pixbo, Jan-Åke Noll, Molndal, and Urban Widlund, and Kerstin Strandberg, Pixbo, Sweden, assignors to AB Stios, Goteborg, Sweden

Filed Nov. 21, 1973, Ser. No. 417,802

Claims priority application Sweden May 21, 1973

Term of patent 14 years

Int. Cl. D24—04

U.S. Cl. D83—1 A

FIG. 1

FIG. 2

FIG. 3

FIG. 4

FIG. 1 is a top perspective view of a first embodiment of a disposable sanitary pad showing our invention; FIG. 2 is a side elevational view thereof;

FIG. 3 is a bottom plan view thereof from the side which is not visible in FIG. 1; and FIGS. 4-6 are views similar to FIGS. 1-3, respectively, but showing a second embodiment of our design.

We claim:

The ornamental design for a disposable sanitary pad, as shown and described.
